GRILLEWORK

Robert T. Bogan, Jr., 2031 Somervell NE.,
Albuquerque, N. Mex. 87112

Filed Aug. 5, 1966, Ser. No. 3,354

Term of patent 14 years

(Cl. D13—1)

FIG. 1 is a front elevation of a grillework embodying my new design, a rear elevation thereof being essentially the same in appearance but with the vertical and horizontal grooves on the rear being interspaced with those on the front;

FIG. 2 is an offset vertical section, taken along line 2—2 of FIG. 1; and

FIG. 3 is an offset horizontal section, taken along line 3—3 of FIG. 1.

I claim:

The ornamental design for a grillework, as shown and described.
